(57) **CLAIM**

The ornamental design for an operating grip for endoscope, as shown and described.

DESCRIPTION

FIG. 1 is a top, front and left side perspective view of an operating grip for endoscope showing my new design; FIG. 2 is a top, rear and left side perspective view thereof; FIG. 3 is a top, front and right side perspective view thereof; FIG. 4 is a bottom, front and left side perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a left side elevational view thereof; and,

FIG. 10 is a right side elevational view thereof.

The broken lines shown in the operating grip for endoscope are for portions that form no part of the claimed design.
